CLAIM

The ornamental design for a lounge chair lockable container, as shown and described.

DESCRIPTION

FIG. 1 is an exploded front perspective view of a lounge chair lockable container comprising our new design; FIG. 2 is a rear exploded perspective view thereof; FIG. 3 is a front perspective view thereof; FIG. 4 is a left side elevation view thereof, the right side elevation view being a mirror image thereof; FIG. 5 is a rear perspective view thereof; and, FIG. 6 is a top plan view thereof.

The broken lines shown in the drawings represent portions of the lounge chair lockable container that form no part of the claimed design.
